UNITED STATES PATENT OFFICE.

BYERS W. KADEL, OF ROANOKE, VIRGINIA.

DRAFT-RIGGING.

1,358,449.

Specification of Letters Patent. Patented Nov. 9, 1920.

Application filed April 19, 1916. Serial No. 22,170.

To all whom it may concern:

Be it known that I, BYERS W. KADEL, a citizen of the United States, residing at Roanoke, in the county of Roanoke and State of Virginia, have invented certain new and useful Improvements in Draft-Rigging; and I do hereby declare the following to be a full, clear, and exact description of the invention, such as will enable others skilled in the art to which it appertains to make and use the same.

The invention relates to the art of draft rigging for railway cars and more particularly to a combined back-stop and tie casting, designed for that class of draft rigging in which the means for operatively connecting the cushioning mechanism and coupler is slidably connected to the latter and in which the back stop and tie casting act to prevent rearward movement of the cushioning mechanism.

While some of the features of my invention may be advantageously embodied in back stops and tie castings generally applicable to any type of underframing, as will appear from the more detailed description, the main feature of the invention, broadly stated, consists in providing a new and improved form of back stop and tie casting for draft rigging for car underframes in which the center sill or sills terminate short of the end sill and forwardly of the bolster. This type of car underframe is shown clearly in my co-pending application Serial No. 47,785, filed August 28, 1915, entitled Car construction, of which application the present application is a continuation in part.

Another feature of the invention consists in providing means on a combined back stop and tie casting, adapted to abut the end or ends of the sill or sills so as to thereby directly transmit the buffing strains thereto and in the line thereof independently of means for connecting the sill or sills and the backstop.

Other features of the invention will appear from a more detailed description thereof, taken in connection with the accompanying drawings chosen for the purpose of illustration.

Throughout the specification and drawings like numerals designate like parts.

Figure 1 is a plan view of a draft rigging and a portion of the car underframe.

Fig. 2 is a side elevation partly in section of the device illustrated in Fig. 1.

Fig. 3 is a section on line 3—3 of Fig. 1, looking in the direction of the arrows.

Figs. 4 and 5 are details of the combined stop and tie casting illustrated in Figs. 1—3 showing, respectively, a view half plan and half horizontal section, and a view in side elevation.

Figs. 6 to 9 are details of another form of combined stop and tie casting adapted for use with a pair of flanged center sills; Fig. 6 being a top plan, Fig. 7 a longitudinal central section, Fig. 8 a side elevation and Fig. 9 a section on line 9—9 of Fig. 7.

Fig. 10 illustrates a combined stop tie casting and center bearing embodying some of the novel features of my invention, and

Fig. 11 is a section on line 11—11 of Fig. 10 looking in the direction indicated by the arrows.

Referring first to the device illustrated in Figs. 1 to 5 inclusive, 1 designates the draft sills which are connected to the end framings 2 and are adapted adjacent their forward ends to receive the coupler guide plate 3, and the coupler carry iron 3^a. On the inner face of each sill and rigidly connected thereto is a stop member 4. The stops 4—4 serve to prevent forward movement of the front follower 5 of the cushioning mechanism 6, which is diagrammatically illustrated by the dotted lines 6^a and which is interposed between the front follower 5 and the rear follower 5^a. The coupler 7 is slidably connected to the yoke 8 so as to permit the rearward movement of the coupler independently of the yoke.

In the special form of connection chosen for the purpose of illustration, the yoke 8 is provided with inturned shoulders 9, 9 adapted to engage the usual shoulders of the coupler butt and in order to prevent the yoke from spreading a band or collar 10 is provided, the said band being adapted to engage the outturned shoulders 11—11 on the yoke. The band or collar 10 is preferably continuous, and while holding the yoke from spreading freely permits the coupler to move rearwardly with reference to the yoke. This particular form of coupler and yoke connection is not my invention, however, but is the invention of one, John A. Pilcher, of Roanoke, Virginia. The numerals 13 and 14—14 designate respectively, the yoke guide and the supporting plates for the yoke.

The rear end of the yoke normally contacts with the coacting face of combined

back stop and tie casting 15 which is rigidly connected to the inner ends of the draft sills 1 and to the forward end of the center sill 1^a in a manner to be hereinafter more fully described.

The draft sills 1 overlap the rearwardly extending flanged members 18 which are preferably formed on the casting 15 and each sill is connected to the adjacent flanged member 18 by the rivets 16 which pass through alined holes 17 provided in the webs of the overlapping members. The flanged members 18 are spaced apart and the flanges 19 thereof preferably extend inwardly. The web 1^c of the center sill 1^a extends between the members 18 and abuts the rib 20 formed on the wall 21 of the said casting; the flanges 1^d of the center sill preferably overlap the flanges 19 of the members 18 and may also abut the upper and lower thickened portions 22 of the wall 21.

The rivets 23 serve to unite the casting 15 and the center sill 1^a, the said rivets passing through and connecting the adjacent pairs of flanges 19 and 1^d on the casting 15 and the center sill 1^a, respectively.

To contact the cushioning mechanism, to hold the same from rearward movement, from normal, I preferably provide the casting 15 with a forwardly projecting tapering portion comprising a transversely extending wall or web 24 adapted to contact with the draft gear, the said wall or web 24 being connected to the wall 21 by means of the vertically extending webs or flanges 25, and 26. The webs 25 may, and preferably do, extend at an oblique angle to the longitudinal axis of the sills. To strengthen the webs 24, 25 and 26 they are preferably provided adjacent their upper and lower edges with flanges such as 27, the said flanges being rearwardly tapering.

The numeral 28 designates one of the car floor plates which is also connected to the casting 15 by means of the upper rivets 23, filler pieces 29 being interposed between the casting 15 and the floor plate 28 as shown. The bottom plate 30 serves as additional means to tie the draft sills to the center sill, the said plate being connected to the flanges of the draft sills 1 by means of the rivets 31 and to the center sill 1^a by means of the lower rivets 23.

The entire buffing load is transmitted to the center sill 1^a as a direct compression by the stop casting 15 owing to the engagement thereof with the center sill, this relieving from strain the means which serve to connect these members together. In buffing the draft sills also are altogether relieved of strains, and all tendency of the same to buckle is avoided. Under draft strains the back stop and tie casting serves to transmit forces from the draft sills 1 to the center

sill 1^a, the rivets and plates 28 and 30 serving to securely tie all of the parts together.

In the form of the device illustrated in Figs. 6 to 9 inclusive, the combined back stop and tie casting 15^a is designed for use on car underframes similar to those heretofore described except in place of the single center sill, a pair of spaced channel-shaped center sills 1^b are employed.

The draft sills 1 are adapted to overlap at their inner ends the forward ends of the center sills 1^b and the stop casting 15^a is adapted to abut the forward ends of center sills. The said casting is preferably provided with a pair of spaced lugs 18^a which extend rearwardly of the forward ends of the center sills 1^b and which are, respectively, adapted to be connected to the adjacent center sill and to a corresponding draft sill by means of the rivets 16^a which pass through alined holes in these members. The respective pairs of draft and center sills are also connected by means of the horizontal rivets 32 and by the upper vertical rivets 33 which pass through the top tie plates 34 and through the upper flanges of the said sills and by the lower vertical rivets which pass through the lower tie plate 35 and the lower flanges of the sills.

The webs and flanges of the channel center sills 1^b contact, respectively, with the thickened portions 20^a and 22^a of the transversely extending webs 21^a. Forwardly of the said webs 21^a the casting 15^a is provided with a transversely extending web or wall 24^a adapted to contact with the draft gear to hold the same from rearward movement. A pair of vertically extending webs 25^a serve to connect the wall 24^a to the thickened portions 20^a of the webs 21^a. Flanges 27^a are formed on the upper and lower edges of the webs 24^a and 25^a to strengthen the same. Upper and lower webs 27^b are preferably provided, each of these webs extends from a flange 27^a on the web 24^a to the web 21^a and serves to strengthen the web 24^a.

To connect the casting 15^a to the cover plate 36, and support the latter, there is provided an angular shaped member 37 which is connected to the ribs 24^a and the upper web 21^a and is connected to the plate 36 by means of rivets 38. In this embodiment of the device also, the entire buffing load is delivered as a direct compression to the center sills by the stop casting independently of the draft sills and the connecting means. The draft strains, however, are transmitted directly to the center sills by the draft sills independently of the stop casting.

In the form illustrated in Figs. 10 and 11 there is shown a combined buffing block, tie casting and center bearing designated generally by the reference numeral 39. The casting 39 is connected to the continuous sills 40 by means of the rivets 41 which pass

through alined holes in the flanges 42 of the casting and the web of the adjacent sill.

Forwardly of the center bearings 43 the casting 39 is provided with a draft gear engaging portion similar to that shown in Fig. 1, except in place of the inclined flanges 27 adjacent the lower edges of the vertical webs there is provided a continuous web or flange 27^c which extends from one flange 10, 25^b to the other flange 25^b as shown, completely closing the space between these flanges except for the openings 44 formed in the said flange 27^c.

In all the forms the combined stop and tie casting is provided with a forward striking portion with vertical walls extending rearwardly from the same, these vertical walls being connected at their upper and lower edges by transversely disposed walls, 15 one or more of these connecting walls being 20 provided with triangularly shaped openings between the vertical walls.

Having now described my invention, what I claim and desire to secure by Letters Patent is:

1. A combined stop and tie casting for draft rigging for railway cars, said casting including a pair of transversely extending webs, a plurality of vertical webs connecting 30 said transversely extending webs, and reinforcing flanges formed on some of the vertically extending webs adjacent the upper and lower portions thereof.

2. A combined stop and tie casting for draft rigging, said casting being provided with a forwardly tapering portion, said tapering portion including a pair of transversely extending webs and a plurality of vertically extending webs connected thereto, 40 at least some of said vertically extending webs being provided with tapering reinforcing flanges.

3. In a car underframe, the combination with a pair of spaced sills, a combined stop and tie casting located between and connected to said sills, said casting including a pair of continuous transversely extending webs and a plurality of vertically extending webs connecting said transversely extending webs, said casting being adapted to abut a portion of the car underframe and being connected thereto, the point of contact between the casting and the underframe being forward of the points of connection between the same.

4. In a car underframe, the combination with a single centrally arranged center sill of less length than the car underframe, of a pair of draft sills overlapping the end 50 of the said center sill, means for connecting said draft sills to the said center sill, said means including a casting which is adapted to straddle the center sill and separate means for connecting said draft sills and 55 said center sill to said casting.

5. In a draft rigging, the combination with the coupler, cushioning mechanism, a yoke for connecting said coupler and cushioning mechanism, draft sills and a center sill, of a combined back stop and tie casting, said casting including a transversely extending web, said web being adapted to contact the said yoke to hold the same from rearward movement and also being adapted to abut the said center sill, to transmit buffing forces thereto directly independently of the draft sills.

6. In a draft rigging, the combination with a car underframe of a single center sill of less length than said underframe, a pair 80 of spaced draft sills, a draft gear between the said sills, a stop casting, said casting transmitting draft forces from said draft sills to the said center sill and abutting the said center sill and transmitting buffing 85 forces thereto independently of the said draft sills, and means for connecting said casting to said center sill and separate means for connecting said casting to the said draft sills.

7. A combined stop and tie casting comprising a forward striking portion, vertical walls extending rearwardly therefrom, said walls being connected at their upper and lower edges by transversely disposed walls 90 and at least one of said last named walls being provided with triangularly shaped openings between the said vertical walls.

8. A combined stop and tie casting for draft riggings, said casting being provided 100 with a tapering forwardly extending portion furnished with a transversely extending web, a second transversely extending web spaced from said first named web and a plurality of upright webs connecting said 105 transversely extending webs, said upright webs being provided with tapering reinforcing flanges along their upper edges.

9. A combined stop and tie casting comprising a striking portion, upright walls 110 extending rearwardly therefrom said walls being provided along their upper edges with transversely disposed flanges, portions of the said flanges being connected to thereby form openings triangular in outline between said upright walls.

10. A combined stop and tie casting comprising a substantially rectangular body portion and a tapering forwardly extending striking portion, upright walls extending 120 rearwardly from and connecting the striking portion to the body portion, a transversely extending wall adapted to connect the upper edges of the said upright walls, said transversely extending wall being provided 125 with triangularly shaped openings located intermediate said upright walls.

11. In a combined backstop and tie casting, a transversely disposed wall adapted to serve as a stop for a movable element 130

- of a draft rigging, a second transversely disposed wall lying to the rear of the first named wall and upright walls serving to connect the two transverse walls, one of said upright walls being centrally located, and means for connecting said transversely disposed walls said means including a member which tapers rearwardly from said first named transversely disposed wall.
12. A combined backstop and tie casting comprising a body portion and a tapering forwardly extending striking portion, said forwardly extending portion including a transversely disposed wall, and a pair of upright side walls, means for connecting the central portion of said transverse wall to said body portion said means comprising a member which tapers rearwardly from

said transverse wall, and a second transversely disposed wall of greater width than the first named wall.

13. In a car underframe, a stop casting provided with a pair of sill adjacent faces and a tapering forwardly extending portion, a transversely extending wall adapted to close the tapering end of the said casting and a second transversely extending wall located in rear of said first named wall, a centrally arranged upright member connecting said walls, said member being provided adjacent its upper end with reinforcing flanges which taper rearwardly from said first named transversely extending wall.

In testimony whereof I affix my signature. 35
BYERS W. KADEL.
